HAIRPIN OR THE LIKE

Abraham Goodman, New York, N.Y., assignor to Dela-mere Company, Inc., New York, N.Y., a corporation of Delaware

Filed Apr. 13, 1960, Ser. No. 60,169

Term of patent 14 years

(Cl. D86—10)

I claim:

The ornamental design for a hairpin or the like, substantially as shown.
